S. VARIVA

RAIL STRAIGHTENING DEVICE

Filed May 13, 1926

UNITED STATES PATENT OFFICE.

STEPHAN VARIVA, OF WHITING, INDIANA.

RAIL-Straightening Device.

Application filed May 13, 1926. Serial No. 108,806.

This invention relates generally to rail straightening devices used to straighten rails, such as used by railroads of all classes, so as to maintain the proper gauge of the 5 rails.

The invention has for an object the provision of an improved rail straightening device easily and quickly operated.

For further comprehension of the invention, and of the objects and advantages thereof, reference will be had to the following description and accompanying drawing, and to the appended claim in which the various novel features of the invention are more 15 particularly set forth.

Fig. 1, of the drawing, is a perspective view of my improved rail straightening device.

Fig. 2, is a side elevational view thereof. 20 Fig. 3, is a perspective rear or bottom view of my improved device.

Fig. 4, is an elevational sectional view taken on the line 4—4 of Fig. 2.

Fig. 5, is a perspective view of the rail 25 clamp, as used in connection with my improved device.

Fig. 6, is a fragmentary side elevational view, illustrating the rail clamp, applied to the rail, as it would appear when in use.

30 Fig. 7, illustrates a modification of the use of the rail clamp.

Fig. 8, is a perspective view of the wrench, as used in connection with my improved device.

35 As here embodied my improved rail straightening device comprises a base 10, suitably reinforced by side elements 11, depending downward therefrom, and having end elements 12, depending downward from the base 10, as a means of supporting the base 10. The base 10 is provided with apertures 13, to removably support clamps 14, adapted to engage the flange 15 of a rail 16. The base 10, has rigidly but removably 40

45 attached thereto as by means of bolts and nuts 17^a, at or near its extremities, supports 17, adapted to engage a rail 16, and a rail 16', and having an elongated aperture 17', longitudinally positioned or located. The

50 base 10, is provided with elongated apertures 18, to slidably accommodate the rail spreading members 19 and 20, adapted to engage the rails 16 and 16', and threadedly attached to the turnbuckle 21, which has a central element 22, provided with serrations

23. The turnbuckle 21, is relatively positioned in the elongated apertures 15, of the base 10, by the positioning member 24, rigidly attached to the said base 10, and provided with a threaded aperture to accommodate the turnbuckle 21. 60

The wrench 25, is provided with a suitable extended element 26, or handle, and has rigidly attached thereto, at or near its lower extremity, hook shaped members 27, depending therefrom, and having pivotally attached thereto, as at 28, an engaging member 29, adapted to engage the serrations 23 of the central element 22 of the turnbuckle 21. 65

The rail clamp 30, is provided with a 70 curved recess 31, adapted to engage the rails 16 and 16', and has attached thereto a depending chain 32.

Referring to the operation and function of my improved device, as above set forth 75 and described; it will be understood, that when the wrench 25, is engaged with the central element 22 of the turnbuckle 21, and pulled in one direction that the turnbuckle 21 will slide the rail spreading members 19 and 20, so that the said rail spreading members 20, so that the said rail spreading members 19 and 20 will engage the rails 16 and 16', so as to force the said rails 16 and 16' 80 against the supports 17, which will cause the rails 16 and 16' to assume the proper gauge, 85 in the event the rails 16 and 16' have spread. It will be further understood that when the rail clamp 30 is engaged with the rails 16 or 16', the depending chain 32 being engaged in the hook shaped member 33 or in the 90 elongated recess 17', that the rails 16 and 16' may be pulled or forced toward one another, which will cause the rails 16 and 16' to assume the proper gauge, in the event the said rails 16 and 16' are further apart than they 95 should be.

It will be clearly understood that the above referred to rails 16 and 16' are those of a railway, either being placed or installed for use, or those of a railway in use, which must 100 be periodically checked up and maintained at the proper gauge, so as to prevent accidents.

While I have above described the preferred form, construction and arrangement 105 of the several elements employed, it will be understood that the device is nevertheless, susceptible of considerable modification therein, and I therefore reserve the privilege of resorting to all such changes as may 110

be fairly embodied within the spirit and scope of the invention as claimed.

Having thus described my invention, what I claim as new, and desire to protect by Letters Patent of the United States, is as follows:

In a device of the class described, the combination with rail gauging means, and rail straightening means having spreading members, of a base placed beneath the rails to

be adjusted, and side and end elements depending downward from the base as a means of supporting the base, the said base being formed with elongated apertures to slidably accommodate the said spreading members, and the rail gauging means and the straightening means being arranged on the base.

In testimony whereof I have affixed my signature.

STEPHAN VARIVA.
